SINK CABINET

Aubrey E. Freshman, St. Louis, Mo., assignor to
 A. E. Freshman Company, a corporation of
 Missouri

Application August 19, 1939, Serial No. 290,980

1 Claim. (Cl. 312—169)

This invention relates to a cabinet structure to fit under a kitchen sink and drain board.

An object of the invention is to provide a cabinet structure adapted to fit under a sink and drain board which is economical in construction, and which is so arranged that it may be quickly and easily installed after the sink is in place without disturbing the sink or its plumbing connections.

Fig. 1 is an elevation showing a cabinet of this invention installed in place;

Fig. 2 is an elevation showing certain parts in position preparatory to installation of the cabinet;

Fig. 3 is a vertical section on line 3—3, Fig. 1;

Fig. 4 is a vertical section on line 4—4, Fig. 1;

Fig. 5 is a horizontal section on line 5—5,

Fig. 1;

Fig. 6 is a view showing certain disconnected parts of the cabinet;

Fig. 7 is a top plan view of a compartment;

Fig. 8 is an elevation showing the compartment;

Fig. 9 shows a modified form of support for the cabinet;

Fig. 10 is a horizontal section on line 10—10,

Fig. 9; and

Fig. 11 is an alternate form of support.

A cabinet embodying this invention is intended to be marketed in parts or sections so arranged that they may be installed quickly and conveniently underneath a sink A, and behind a roll or skirt B of the sink. The separate parts of the structure include a front portion or assembly 1, one or two side panels 2, a compartment and drawer support 3, a side or fastening strip 4 and drawer 5.

The arrangement is such that the front assembly 1 may be tilted so it may be pushed in place behind the skirt or roll B of the sink and drain board. After the front assembly is in position the side panel or panels 2 may be added and then the compartment and drawer support 3 may be secured to the front assembly in a manner and by a means which will be described later in detail. Then with the insertion of the drawer 5 the erection is complete.

The front assembly includes a panel 6 which has openings covered by doors 7 and 8, fastened by hinges to the panel 6. It has an opening to receive the drawer 5 and a like opening covered by a door 9, also hinged to the panel 6. The door 9 is on the order of a false drawer and may carry a pocket compartment 10. Its principal purpose is to give symmetry to the cabinet front by 55

matching the drawer 5. As specifically illustrated the front assembly also includes a side wing 11, a bevel corner member 12 and a wing member 13, having a groove 14 to receive the end of the side panel 2 and to which the side panel is secured.

As specifically shown, the structure is intended for a left hand drain board. It will be obvious, of course, that the parts may be reversed so that the cabinet may be adapted for a right hand drain board. It will also be obvious that both ends of the front construction may be similar, in which case two side panels 2 will be used, and this will be the case where the cabinet has to fit a sink having both ends spaced from the walls of the room.

The compartment 3 is open at the front to correspond with the opening covered by the door 7 and comprises a top wall 15, bottom wall 16, back wall 17 and end walls 18. Runners 19 for the drawer 5 are secured to and supported by the top wall 15 of the compartment 3.

The compartment 3, as shown in Figs. 2, 7 and 8, is completely detached from the front assembly 1 until the cabinet is installed. Convenient means have been provided whereby the compartment may be placed and held in assembly with the front portion. Blocks or guide strips 20 are secured to the inner face of the panel 6, one on each side of the opening covered by the door 7. These blocks are bevelled at their tops as shown in Figs. 3 and 4. Blocks 21 are secured at the forward edge of the walls 18 with their lower ends bevelled complementary to the bevel of the blocks 20. Thus when the compartment 3 is lifted and placed between the blocks 20 and then lowered, the lower end of the blocks 21 will interlock with or fit behind the bevel on the upper ends of the blocks 20, as clearly shown in Fig. 4.

A sill 22 is secured to the inner face of the panel 6 below the opening of the door 7 and forms a support for the compartment 3 and is to be engaged by the forward bottom edge of the bottom wall 16. After the compartment 3 has been placed in position with respect to the front assembly 1, it may be fastened by screws through the bottom wall 16 into the sill 22.

It has already been explained that the cabinet, before installation, consists of several separate parts. The first step of installation is shown in Fig. 2, where the strip or stile 4 has been secured to the wall of the room by screws. The compartment 3 is set in proper upright position on the floor beneath the drain board of the sink. Then the front assembly 1 is placed in position

by tilting its upper edge forward so that it will go under and behind the skirt or roll B on the sink, and the front assembly 1 is then brought to proper vertical position. The compartment 3 may then be lifted so that the lower ends of the blocks 21 fit behind the upper ends of the blocks 20 with the blocks 20 engaging the side walls 13 of the compartment. With the door 7 open, one or more screws may be inserted through the forward edge of the bottom wall 16 into the sill 22. The compartment has thus been secured in position. The side panel 2 may be secured in position by screws passing through its edges into the wing 13 and into the stile 4. Since the runners 19 are a part of the compartment and have been secured in proper relationship when the compartment was placed in position, the drawer 5 may then be inserted and the installation is complete.

Various means may be provided for accommodating a commercial structure to different heights of sinks; one means is to make the front assembly 1 and the side panel 2 of maximum height, so that these parts may be trimmed to proper height for a particular installation.

Another means for accommodating a structure to different heights is shown in Figs. 9 and 10, in which adjustable legs 23 are provided. While only one leg 23 is shown in the drawings, it will be understood that at least two will be required. The leg 23, specifically shown, has a slot 24. A strap or clip 25 bridges the slot 24 and a screw 26 passes through the clip and the slot into the panel 6. It will be obvious that by loosening

the screw 26 the leg 23 may be adjusted for height.

Another means is shown in Fig. 11, which consists in supplying overlapping baseboards 27 which may be attached by screws 28 to the front assembly 1, as well as to the panel or panels 2 when the cabinet is assembled.

While the structure specifically shown in the drawings is of wood, it will be understood, of course, that the invention may be embodied in metal. It will also be obvious that while particular details of construction are shown, various changes may be made, within the scope of the appended claim, without departing from the spirit of this invention.

I claim:

A knock-down cabinet structure adapted to be installed under a sink and drain board including a unitary front structure which can be tilted for installation back of a skirt on the sink in a vertical position and having an opening closed by a door and a second opening above and in alignment with the first mentioned opening to accommodate a drawer, a detachable compartment open at its front to register with the first mentioned opening in the front structure, drawer runners secured to the upper surface of said compartment, means secured to the inner surface of the front structure adjacent said opening on which said compartment may be arranged after the front structure is in vertical position as aforesaid to support the compartment.

AUBREY E. FRESHMAN.
